Primary Examiner — Eliza Z Harvey(74) *Attorney, Agent, or Firm* — Philip H. Burrus, IV(57) **CLAIM**

The ornamental design for hanger system, as shown and described.

DESCRIPTION

FIG. 1 is a first perspective view of a hanger system, showing our new design;

FIG. 2 is a second perspective view thereof;

FIG. 3 is a third perspective view thereof;

FIG. 4 is a fourth perspective view thereof;

FIG. 5 is a right elevation view thereof;

FIG. 6 is a left elevation view thereof;

FIG. 7 is a front elevation view thereof;

FIG. 8 is a rear elevation view thereof;

FIG. 9 is a top plan view thereof; and,

FIG. 10 is a bottom plan view thereof.
